DISPOSABLE POCKET LIGHT

Lew F. Allyn, Skaneateles, N.Y., assignor to Welch Allyn Inc., Skaneateles Falls, N.Y., a corporation of New York

Filed Sept. 4, 1969, Ser. No. 19,018

Term of patent 14 years

Int. Cl. D26—04

U.S. Cl. D48—24

FIG. 1 is a front elevation of a disposable pocket light embodying my new design;

FIG. 2 is a right side elevation thereof, the left side being a mirror image of the right side;

FIG. 3 is a rear elevation thereof;

FIG. 4 is a top plan view thereof;

FIG. 5 is a bottom plan view thereof; and

FIGS. 6 and 7 are transverse sectional views taken substantially on lines 6—6 and 7—7, respectively, of FIG. 2.

I claim:

The ornamental design for a disposable pocket light, substantially as shown and described.
